UNITED STATES PATENT OFFICE.

THOMAS LONG, OF BOSTON, MASSACHUSETTS.

CENTRIFUGAL DRYING-MACHINE.

SPECIFICATION forming part of Letters Patent No. 462,495, dated November 3, 1891.

Application filed May 3, 1889. Serial No. 309,435. (No model.)

To all whom it may concern:

Be it known that I, THOMAS LONG, a citizen of the United States, and a resident of Boston, in the county of Suffolk and State of Massachusetts, have invented a new and useful Improvement in Centrifugal Drying-Machines, of which the following is a full, clear, and exact description, reference being had to the accompanying drawings, forming a part of this specification, in explaining its nature.

The invention relates to a centrifugal drying-machine having a perforated shell or case in the form of an inverted cone, a feed-pipe for feeding the substance to be dried or freed from liquid to the chamber or cup formed by the cone, a horizontal table extending from the upper edge of the cone-shell, having channels of peculiar shape separated by perforated walls or screens, whereby the operation of drying or separating the liquid from the solid is commenced in the cup and is continued during the passage of the substance or material from the cup through the channels until discharged at the outer edge of the table, preferably over an outwardly-inclined board.

The invention further relates to a centrifugal drying apparatus having the outer shell or surface inclosed by a chamber in which there is a partial vacuum.

The invention further relates to various features of construction and organization, all of which will hereinafter be described.

In the drawings, Figure 1 is a view, principally in vertical central section, of a machine having the features of my invention. Fig. 2 is a view in plan inverted of a portion of the machine. Fig. 3 is a view, principally in plan, representing various portions of the upper part of the machine, some of the plates being broken out to better show them. Fig. 4 is a section upon the line $y-y$ of Fig. 3, drawn to a large scale. Fig. 5 is a view in plan of the plate forming the bottom of the vacuum-chamber hereinafter referred to and representing the blades which form an exhaust-fan.

A is the inverted conical shell. It is mounted upon the upper end of the shaft a , and it has the holes or passages a' extending from its cup or chamber a^2 to the chamber a^3 , which surrounds the shell. The shell is also lined upon its inner side with wire-gauze a^4 of any desired mesh. Generally for most purposes

a very fine mesh is used. There extends from the upper edge of the shell A a flange a^5 , to which is bolted a table a^6 . Upon this table there is arranged a number of curved channels a^7 . (See Fig. 3.) These channels are formed, preferably, by means of a casing or partition a^8 , (see Fig. 4,) bolted or otherwise secured to the table a^6 . Each of these partitions a^8 preferably has the flat base a^9 , the inclined upwardly-extending section a^{10} , and the horizontal section a^{11} , having a shoulder a^{12} , which is substantially in line with the lower edge a^{13} of the base. To the shoulder a^{12} and edge a^{13} is secured wire-gauze a^{14} of any required mesh, and a portion of the horizontal section a^{11} extends beyond the wire-gauze and forms a partial cover. The wire-gauze forms, in connection with the inclined section a^{10} , a drainage-channel a^{15} , which also extends to the edge of the table. Each partition a^8 is preferably curved, as represented in Fig. 3, from near the inner edge of the table in a forward direction toward the edge of the table. This curved section extends very nearly to the outer edge of the table and then becomes radial. (See Fig. 3.) Each section or partition a^8 also gradually increases in width from its inner end to its outer end, and the inner end has preferably rounded corners a^{16} . Each of the channels a^7 gradually increases in width from its inner end to its outer end, and at the outer end of each channel there is the inclined board or barrier a^{17} , which extends upward and outward from the upper surface of the table a^6 . Each of the channels a^{15} is open at its outer end. An annular plate B is attached to the upper surface of the partitions a^8 to partially cover the cup a^2 and the inner ends of the passages a^7 . A plate C is also secured to the shell A below the holes a' . This plate forms, in connection with the shell A and table a^6 , the chamber a^3 , which is open outwardly into the chamber D. This chamber preferably is divided by division-plates c' into the sections c^2 , in each of which there is a number of blades c^3 , forming an exhaust-fan. (See Fig. 5.) The shaft a is mounted in suitable bearings in the frame E of the machine, and is rotated by the pulley e. The chamber D is formed about the plate C and table a^6 by means of the bottom plate d of the frame, the inclined curved plate d' and

the vertical plate d^2 , which is curved or extended inward at its top to form as close a joint between the edge of the table about the partitions as possible. Into this chamber D 5 the drain-channels a^{15} and the exhaust-chamber a^3 open, and there is an outlet-passage d^3 extending from the bottom of this chamber D. The substance or material to be dried is fed continuously to the cup a^2 , preferably 10 through the feed-pipe F, the lower end f of which is within the cup a^2 , and is enlarged to form a section in the shape of a frustum of a cone, the edge of which is separated from the interior lining or gauze of the cup by a 15 quite narrow space. The substance or material fed through the feed-pipe falls upon the separating-plate G, forming the bottom of the cup a^2 . This separating-plate has an upwardly-extending cone g, which serves to separate 20 the material and throw it toward the sides of the cup, and also the cutters g', which are preferably made from flat sheet metal bent to the shape of a hook and fastened to the upper surface of the separator-plate.

25 In operation the substance or material to be dried, or separated, or freed from fluid, is fed continuously through the feed-pipe in a volume varying as to quantity, according to the nature of the material or substance. The 30 cup rapidly rotates, and the fluid is expelled through the wire-gauze and holes a' into the chamber a^8 . The solid material is by the action of the machine lifted up the inclined surface of the cone into the lateral passages 35 a^7 , and by the rapid rotation of the machine is thrown and held against the-perforated-gauze walls a^{14} of the partition-plates while it is being moved outward, so that a continued 40 separation of the fluid element from the solid element takes place after the material has been forced up from the cup into the channels a^7 , the fluid being forced through the perforated walls a^{14} into the escape-channels a^{15} . The material is thus forced in continuous 45 streams through the various channels a^7 , being somewhat retarded at the outer ends of the channels by the inclined bottom a^{17} , up which it is gradually worked or forced by the centrifugal action and from the outer 50 edge of which it falls or is thrown over the edge of the plate d^2 into the passage between it and the jacket H. A covering-plate h extends from the jacket H over the inclined boards a^{17} and acts to prevent the material 55 from being thrown upward or away from the machine, and an apron h' of canvas or other flexible material is suspended from the plate h in line with the passage h^2 , through which the contents are discharged, to break 60 the outward force thereof and also to prevent it from sticking against the inner surface of the jacket H and plate d^2 and from clogging the machine. It will thus be seen that the fluid is forced from the solid first 65 into the chamber a^8 , from which it escapes into the chamber D and outlet d^3 , and then

through the perforated walls a^{14} into the channels a^{15} , which discharge into the chamber D. The rapid rotation of the machine causes the blades c^3 to act as exhaust-fans 70 and thus reduce the air-pressure upon the outer side of the cup a^2 and also the inner side of the perforated walls a^{14} . In lieu of the blades c^3 there may be connected with the chamber a^8 and drain-channels a^{15} an exhaust-fan, and I have represented in Fig. 1 an exhaust-fan H', which is connected with the chamber D and shuts or draws the air from about the cup a^2 and from the channels a^{15} . This reduction of pressure upon the outer 80 side of the portion of the machine through which the fluid is forced is an improvement, in that in addition to the centrifugal force an atmospheric force consequent upon the variation in pressure between the two sides 85 of the machine—that is, the side which contains the substance being separated and the outer side which receives the liquid—is exerted, only, of course, the more complete the vacuum the greater this difference of pressure 90 and the more effective is the operation of the machine from this cause. The degree of the curvature of the partitions a^8 may of course be varied from that represented in Fig. 3 without departing from the spirit of the 95 invention.

In operation the rotation of the machine causes the material to be driven up the side of the chamber and to take the form of a thin sheet or layer upon the table, the front 100 walls of the partition a^8 coming in contact with the overflowing layer and with more or less stress or force, according to the rapidity with which the machine is operated, and tending to exert a pressure or stress against the material to such an extent as to cause it to be held against the screens a^{14} with such force that the fluid is expelled through the screens into the channels behind, while at the same time the curve of the walls and channels a^7 is such that the material is moved outward to the edge of the table, still keeping, however, its contact with the screens or perforated walls a^{14} . This combination of the centrifugal action of the cup and the rotative action 110 of the curved perforated walls upon the material is such that I am enabled to obtain a practically-continuous drying operation and to continuously feed the machine with the material to be dried.

The construction of the machine is such that the air during the operation of the machine does not act to retard the centrifugal and rotary forces employed in causing the forcible separation of the liquid from the solid 115 portions of the material.

Having thus fully described my invention, I claim and desire to secure by Letters Patent of the United States—

1. In a centrifugal drying machine, the 120 combination of a perforated gauze-lined inverted-cone-shaped shell, a rotary table ex-

tending from the upper edge of said shell, and curved drying-partitions arranged thereon, forming escape-channels, and having perforated walls with which the material is held in contact and along which it is moved by the operation of the machine, as and for the purposes described.

2. In a centrifugal drying-machine, the combination of a perforated gauze-lined inverted-cone-shaped shell, a rotary table extending from the upper edge of said shell, curved partitions forming escape-channels arranged on said table, the working wall of each partition being perforated, as described, and the outer end of each channel being inclined upwardly and outwardly, as and for the purposes specified.

3. In a centrifugal drying-machine, the combination of a perforated gauze-lined inverted-cone-shaped shell, a rotary table extending from the upper edge of said shell, the curved partitions arranged thereon having perforated walls, as specified, and forming channels which gradually enlarge from their inner ends outwardly, substantially as and for the purposes described.

4. In a centrifugal drying-machine, the combination of a perforated gauze-lined inverted-cone-shaped shell, a rotary table extending from the upper edge of said shell, curved partitions arranged thereon forming escape-channels, the said partitions having perforated walls and being shaped to form channels which are curved to near the edge of the table and are then radial, substantially as described.

5. In a centrifugal drying-machine, the rotary drying-table having the curved partitions, and perforated walls carried by said partitions where the curved channels a^7 and the drainage-passages are formed, substantially as described.

6. The combination of the table a^6 and a number of partitions a^8 , secured to the table to form passages a^7 and shaped to provide points for the attachment of the wire-gauze a^{14} , and the wire-gauze a^{14} , attached to said partition whereby the drainage-channels a^{15} are formed, substantially as described.

50 7. The combination, in a centrifugal drying-machine, of the rotary table having the

curved channels a^7 , the perforated walls a^{14} , and the partial covering-plate a^{11} , substantially as described.

8. The combination, in a centrifugal drying-machine, of the rotary perforated gauze-lined inverted-cone-shaped shell, the table a^6 , having curved channels extending from the top of the shell, each of which channels has a perforated back wall a^{14} , the inclines a^{17} at 60 the ends of the channels, and the covering-plates B h , substantially as described.

9. The combination, in a centrifugal drying-machine, of the perforated gauze-lined inverted-cone-shaped shell, the table a^6 , the 65 curved channels a^7 having the perforated back walls a^{14} , the inclined ends a^{17} , covering-plates B and h , and apron h' , substantially as described.

10. The combination of the perforated 70 gauze-lined inverted-cone-shaped shell, the table having the curved channels a^7 , and perforated walls a^{14} , the drainage-channels a^{15} , the drainage-chamber a^8 , and an exhaust apparatus for exhausting air from said drainage-channels and said drainage-chamber, substantially as described.

11. The combination of a stationary shell forming the chamber D and having an outlet, the rotary perforated gauze-lined inverted-cone-shaped shell, and the table having curved escape-channels a^7 , arranged to discharge their contents over the edge of the casing, and the drainage-channels a^{15} , and drainage-chamber about the shell A , opening 85 into the said chamber D , substantially as described.

12. The combination, in an organized centrifugal drying-machine, of a rotary perforated shell, a rotary table having a series of 90 channels extending from said shell, a drainage and air-exhaust passage substantially parallel with each of said channels and separated therefrom by a perforated wall, and an air-exhaust chamber inclosing or partially 95 inclosing said perforated shell and into which said drainage-channels open, as and for the purposes specified.

THOMAS LONG.
